UNITED STATES PATENT OFFICE.

MAX FIRESTONE, OF DETROIT, MICHIGAN, ASSIGNOR TO FIRESTONE RADIATOR MANUFACTURING COMPANY, OF DETROIT, MICHIGAN, A CORPORATION OF MICHIGAN.

RADIATOR.

Application filed September 7, 1920. Serial No. 408,725.

To all whom it may concern:

Be it known that I, MAX FIRESTONE, a citizen of the United States of America, residing at Detroit, in the county of Wayne and State of Michigan, have invented certain new and useful Improvements in Radiators, of which the following is a specification, reference being had therein to the accompanying drawings.

10 This invention relates to devices for dissipating the heat of fluids and more particularly to a cooling device or radiator particularly adapted for use in motor vehicle construction. An object of the invention is to 15 provide a core which is simple in construction and efficient in operation, the radiating or heat dissipating fins between water tubes being so constructed as to deflect the air passing through the radiator, thereby securing 20 a maximum cooling effect.

A further object is to provide means for preventing the water from freezing in the radiator tanks under ordinary circumstances, said means comprising a jacket surrounding 25 the tanks, the jacket for the top tank being connected with the jacket of the bottom tank to provide a free circulation of an insulating medium contained within these jackets.

It is also an object of the invention to 30 provide certain other new and useful features in the construction and arrangement of parts all as hereinafter more fully described and particularly pointed out in the appended claim.

35 With the above and other ends in view, the invention consists in the matters hereinafter set forth, and more particularly pointed out in the appended claim, reference being had to the accompanying drawing, in 40 which

Figure 1 is a transverse vertical section substantially upon the line I—I of Fig. 2, of a radiator construction illustrative of the invention and showing the radiator core 45 in front elevation;

Fig. 2 is a vertical section substantially upon line II—II of Fig. 1;

Fig. 3 is an enlarged detail of the core construction showing a portion of a water 50 tube with a fin plate in position thereon; and

Fig. 4 is a perspective view of Fig. 3.

As shown in the drawing 1 indicates a bottom tank and 2 a top tank of any desired 55 form or configuration and between these

tanks is a fabricated core 3 comprising vertical tubes 4 which open at their lower ends into the bottom tank and at their upper ends into the top tank, said tubes being secured in spaced relation in any suitable 60 manner. These tubes are each of elongated form, their sides being substantially flat and are constructed from a single piece of sheet metal folded upon itself with the side edges overlapped and soldered together as 65 at 5, forming a closed flat tube which is elongated transversely to extend from the front face of the core to the rear face thereof. Between adjacent tubes are placed fin plates 6 each formed of a single strip of 70 thin sheet metal which is corrugated transversely with the apices of the corrugations contacting the flat sides of the adjacent tubes to dissipate the heat of the water passing through these tubes and form a plurality 75 of air passages extending transversely of the core between the several tubes. These corrugations 7 of the fin plates are preferably of tortuous form in the direction of their length from the front to the rear faces 80 of the core, each corrugation having a downwardly inclined portion 8 adjacent the front face of the core and meeting at substantially the center line of the core, and upwardly inclined portion 9 extending to near the rear 85 face of the core. The front and rear end portions 10 and 11 of each corrugation extend in substantially a horizontal plane inwardly from the front and rear faces of the core for a short distance, meeting the 90 inclined portions 8 and 9. These corrugations therefore divide each air space between adjacent water tubes into a large number of air passages and the air entering the forward end of each passage is deflected by coming into contact with the downwardly inclined portion 8 of the corrugation and is again deflected by coming into contact with the upwardly inclined wall 9 of the corrugation so that in passing through the 95 core these air streams are deflected from side to side into contact with the walls of the corrugations and a much greater cooling effect is secured thereby, a greater proportion of the radiated heat being carried 100 away by the air currents due to their intimate contact with the radiating fin plates in passing through the great number of air passages formed by the corrugations. The front end portion 10 of each air passage 105

110

being extended horizontally for a short distance, directs the entering air into the passages in a horizontal direction and against the inclined wall 8 of the corrugation 5 and in leaving the passage the air is again deflected into a horizontal direction by the horizontal end portion 11 of the passage, the air issuing therefrom in a direction directly toward the engine to which 10 the radiator is connected in the usual manner.

The water tubes 4 being substantially flat with their side walls formed of thin sheet metal and extending in parallel spaced relation, the freezing of the thin body of water contained in these tubes will not crack the tubes and cause them to leak for the reason that the expansion of this thin body of water upon freezing will not be great enough to 20 extend these walls beyond the limit of their flexibility as the metal is very thin and the wall is flat and free to bend between the line of contact of the fin plates therewith and these fin plates being of very thin metal and 25 corrugated will also yield sufficiently to provide for any expansion of water contained in the tubes when it freezes.

It is common practice to use a portion of alcohol or other non-freezing fluid in the 30 circulating water to prevent the freezing of the water, but it is found that such mixture is not entirely satisfactory due to the fact that it causes foaming when the circulating water becomes heated. It is therefore desirable to provide some means whereby the 35 use of such a fluid becomes unnecessary and in the present construction this provision is made by forming the water tank 1 and the top tank 2 with a double outer wall 40 which provides a space or jacket 12 enclosing these tanks, except at the places of connection of the tubes 4 with the tanks. Within 45 this jacket or space 12 may be placed a non-freezing fluid through a fill opening 13 and the jacket surrounding the top tank 2 is preferably connected with the jacket of the bottom tank 1 in some suitable manner, as by providing vertical walls 14 and 15 which are spaced apart at each end of the 50 radiator and provide vertical end passages 16 connecting the space or jacket along the upper tank with the jacket of the lower

tank. The non-freezing fluid is thus free to circulate from one to the other of the jackets and the vertical passages 16 provide insulating columns of fluid at the ends of the core. Each water tank is thus enclosed by an insulating jacket and protected against freezing under normal conditions so that each will contain a body of fluid even though 55 the water tubes 4 of the core should freeze solid. Therefore the engine may be started without danger of injury due to lack of water as the tanks will always contain a sufficient quantity to provide for the running of the engine for a short time which will heat this water and will gradually thaw out the frozen tubes. The necessity for placing a non-freezing fluid in the circulating water is therefore obviated under ordinary weather temperatures as the construction of the core is such that it is not affected or injured by the freezing of the water contained therein and the jacketing 60 of the tanks prevents the water in these tanks from freezing.

Obviously changes may be made in the form and construction of the several parts and within the scope of the appended claim without departing from the spirit of my 65 invention and I do not therefore limit myself to the particular construction shown.

Having thus freely described my invention, what I claim is:

In a radiator, wherein a core is composed of flat parallel spaced tubes, spacers for such tubes composed of fin plates formed with a plurality of transverse corrugations with the apices of the corrugations in contact with the flat side walls of the adjacent tubes, said corrugations being formed with downwardly inclined intermediate portions meeting upwardly inclined intermediate portions and said intermediate portions meeting horizontal end portions to form tortuous air passages extending from the front to the rear of the radiator core.

In testimony whereof I affix my signature in presence of two witnesses.

MAX FIRESTONE.
